Fig. 20Fig. 21Fig. 1 is a front elevational view of a rosary showing our new design;

Fig. 2 is a rear elevational view thereof;

Figs. 3 and 4 are, respectively, front and rear perspective views of the rosary bead 22 of Figs. 1 and 2;

Figs. 5 and 6 are, respectively, front and rear perspective views of rosary bead 23 of Figs. 1 and 2;

Figs. 7 and 8 are, respectively, front and rear perspective views of rosary bead 24 of Figs. 1 and 2;

Figs. 9 and 10 are, respectively, front and rear perspective views of rosary bead 25 of Figs. 1 and 2;

Figs. 11 and 12 are, respectively, front and rear perspective views of rosary bead 26 of Figs. 1 and 2;

Fig. 13 is a front perspective view of rosary bead 27 of Figs. 1 and 2, the opposite side being the same as that shown;

Figs. 14 and 15 are, respectively, front and rear perspective views of rosary bead 28 of Figs. 1 and 2;

Figs. 16 and 17 are, respectively, front and rear perspective views of rosary bead 29 of Figs. 1 and 2;

Figs. 18 and 19 are, respectively, front and rear perspective views of rosary bead 30 of Figs. 1 and 2; and

Figs. 20 and 21 are, respectively, front and rear perspective views of rosary bead 31 of Figs. 1 and 2.

The dominant features of our design reside in those portions shown in full lines.

We claim:

The ornamental design for a rosary or the like, as shown and described.
